Attorney

UNITED STATES PATENT OFFICE.

ORA L. FITCH, OF POINT MARION, PENNSYLVANIA.

LEVEL.

Application filed April 12, 1924. Serial No. 706,128.

To all whom it may concern:

Be it known that I, ORA L. FITCH, a citizen of the United States, residing at Point Marion, in the county of Fayette and State of Pennsylvania, have invented certain new and useful Improvements in a Level, of which the following is a specification.

This invention relates to new and useful improvements in levels which are principally adapted for use in connection with determining the angularity or inclination of a level with respect to a horizontal plane.

One of the important objects of the present invention is to provide a level of the above mentioned character, which will enable a person to accurately ascertain the level of a wall or other object on which the device is positioned.

A still further object of the present invention is to provide a level of the above mentioned character, which is of such a construction as to enable the reading of the same to be visible from both sides of the stock of the level.

A still further object of the present invention is to provide a level of the above mentioned character, wherein means is associated with the pendulum supporting means whereby the same is adapted for lateral adjustment.

A further object of the present invention is to provide a level of the above mentioned character, which is simple in construction, inexpensive, strong and durable and furthermore adapted for the purposes for which it is designed.

Other objects and advantages of this invention will become apparent during the course of the following description.

In the accompanying drawing forming a part of this specification and in which like numerals designate like parts throughout the same:

Figure 1 is a fragmentary side elevation of my level, and

Figure 2 is a vertical section taken approximately on line 2-2 of Figure 1.

In the drawing wherein for the purpose of illustration is shown the preferred embodiment of my invention, the numeral 1 designates the stock which is formed of wood and the same is preferably rectangular in design. The stock 1 is further provided with a central circular opening which extends transversely therethrough and is indicated by the numeral 2 in the drawing. The

edge of the circular opening 2 is substantially of inverted V-shape in cross section in the manner clearly illustrated in Figure 2 of the drawing. The purpose of this construction will hereinafter be more fully described.

Adapted to be secured in any suitable manner on the lower portion of the inverted V-shaped edge of the circular opening 2 is 65 the inverted V-shaped segmental member 4, the same fitting snugly on the inverted V-shaped edge 3 in the manner clearly illustrated in Figure 2 of the drawing. The segmental member 4 is provided with grad- 70 uations on its outer side in the manner shown in Figure 1 so as to render the level readable from both sides of the stock.

Secured to the opposite sides of the stock 1 above the central opening 2 are the upper portions of the plates 5 and 6 respectively. The plates are preferably set in the upper portions of the sides of the stock by morticing cut the upper portion of the respective sides of the stock. Any suitable fastening means such as is shown at 7 is provided for supporting the upper portions of the plates in the morticed portions of the opposite sides of the stock. The lower portions of the plates 5 and 6 extend downwardly adjacent the central opening 2 and adapted to be pivotally supported between the lower ends of the plates 5 and 6 respectively and disposed within the central opening 2 is the pendulum designated generally by the numeral 8.

The pendulum 8 has the laterally extending member 9 formed on the upper end thereof which provides a means for pivotally supporting the pendulum between the lower ends of the plates and the pendulum 8 furthermore has provided on its lower end the weight 10 from which extends the forked or bifurcated portions 11 and 12 respectively. This arrangement provides a means whereby the forked portions extend over the converging edge of the segmental member and each fork provides a pointer or indicator in connection with the graduations provided on the inverted V-shaped member in the manner clearly illustrated in the drawing. It is of course to be understood that the inner opposed faces of the lower ends of the plates 5 and 6 are provided with suitable cavities or recesses for receiving the ends of the lateral extension 9 whereby the pendulum may be properly supported by

the plate in the central opening so as to cooperate with the graduated segmental member 4.

Extending inwardly from each of the plates 5 and 6 respectively adjacent the lower ends thereof are the cooperating lugs 13 and 14 respectively. The lug 13 is provided with an internally threaded bore, while the lug 14 is provided with a longitudinally extending opening through which is adapted to extend the bolt 15. The inner end of the bolt 15 is threaded into the threaded recess provided in the lug 13 while the head of the bolt engages the outer face 15 of the side plate 6 in the manner clearly illustrated in Figure 2. The purpose of the lugs and the securing bolt 15 is to provide a means whereby the plates may be adjusted so as to properly support the lateral extension 9 of the pendulum 8 and thus hold the pendulum in an operative position and against accidental displacement from between the plates.

It will thus be seen from the foregoing description, that a level has been provided which may be used for determining the angularity or inclination of a level with respect to a horizontal plane and will further be accurate and positive in its use. The provision of a level of this character enables the same to be manufactured at a very low cost, the parts being further arranged as to permit the same to be readily disassembled whenever necessary and thus further provides a means whereby the level may be read from either side of the stock. The parts further provided are of such a construction as not to be easily broken or to be rendered inoperative should the level be dropped accidentally or struck.

While I have shown the preferred embodiment of my invention, it is to be understood that various changes in the size, shape and arrangement of parts may be resorted to without departing from the spirit of the invention and the scope of the appended claims.

Having thus described my invention, what I claim is:

1. A level comprising a stock having a central circular opening, a segmental mem-

ber supported in the lower portion of said opening, said segmental member being substantially of inverted V-shape in cross section and having graduations on the outer faces thereof, a pair of plates secured on opposite sides of the stock and arranged adjacent said opening, a weighted pendulum pivoted at its upper end between the lower ends of said plates and extending downwardly in said opening, the lower end of the pendulum being bifurcated to cooperate with the graduation on the segmental member, means associated with said plates for holding the same in adjusted position, said means comprising a pair of aligned cooperating lugs extending inwardly from said plates respectively adjacent the lower ends thereof, and a bolt extending through one of said plates and an opening provided in the lug carried thereby and threaded into the lug carried by the opposite plate.

2. A level of the class described comprising a stock having a central transverse opening provided therein, the edge of said opening being substantially of inverted V-shape in cross section, a segmental member of inverted V-shape in cross section supported on the lower portion of the inverted V-shaped edge of the opening, said segmental member having graduations provided on the outer faces thereof, a pair of plates secured at their upper ends on the opposite sides of the stock, said plates extending downwardly adjacent said opening, a pendulum pivotally supported at its upper end between the lower ends of said plates, the lower end of said pendulum having a weight associated therewith, a pair of indicators arranged on the lower end of said pendulum and cooperating with the inverted V-shaped segmental member, and means for holding said plates in adjusted position, said means comprising a pair of aligned cooperating lugs extending inwardly from the plates respectively adjacent the lower ends thereof, and a bolt extending through one of the plates and an opening provided in the lug carried thereby, said bolts being threaded into the lug carried by the opposite plate.

In testimony whereof I affix my signature.

ORA L. FITCH.
